APPARATUS FOR CALKING FINS

Wilhelm B. Bronander, Montclair, N. J.

Application May 27, 1944, Serial No. 537,705

2 Claims. (Cl. 80—19)

1

This invention relates to cooling fins. More particularly stated, the invention relates to a method of calking cooling fins and to a machine for securing fin sections to the wall of an element to be cooled. This application is a continuation in part of application Serial No. 464,627, filed November 5, 1942, now Patent No. 2,379,879, granted July 10, 1945.

This invention has for its salient object to provide a method of and apparatus for applying cooling fin sections to an element to be cooled, so arranged and so constructed that the fin sections will be accurately and securely anchored or calked.

Another object of the invention is to provide a method of and apparatus for calking cooling fins so worked out and so constructed that the tubular wall to which the sections are secured will not be distorted or forced out of alignment.

Another object of the invention is to so secure or calk the fins that each fin section will be forced into its groove and anchored or calked therein with the required force.

Further objects of the invention will appear from the following specification taken in connection with the drawings which form a part of this application, and in which

Fig. 1 is a top plan view of a machine constructed in accordance with the invention;

Fig. 2 is an elevation showing the drive for the mandrel on which the member to be provided with fins is mounted;

Fig. 3 is an enlarged sectional elevation taken substantially on line 3—3 of Fig. 1, looking in the direction of the arrows;

Figs. 4 and 5 are respectively sectional elevations taken substantially on lines 4—4 and 5—5 of Fig. 3, looking in the direction of the arrows;

Fig. 6 is a plan view of one of the trays for supporting the presser bars which calk the fin sections in the grooves;

Fig. 7 is a longitudinal sectional elevation of the tray shown in Fig. 6;

Fig. 8 is an elevational view and Fig. 9 is a plan or edge view of one of the presser bars;

Fig. 10 is an elevational view of one of the spacing and alining plates for alining the presser bars;

Fig. 11 is a plan view of the plate shown in Fig. 10;

Figs. 12 and 13 are elevation and plan views respectively of one of the segmental plates used for insuring the proper parallel relation of the fin walls;

2

Fig. 14 is an enlarged sectional elevation showing the fins in the grooves before and after calking;

Fig. 15 is a fragmentary sectional elevation showing the manner of use of the segmental spacing or fin wall positioning plates; and

Fig. 16 is a sectional elevation showing particularly the staggered mounting of the fin sections.

The invention briefly described consists of a method and machine for calking fin sections to the wall of a cylinder or other element on which the sections are to be mounted. The cylinder or wall is mounted on a rotatable mandrel and the fin sections are initially placed in grooves around the wall. The fin sections consist of double walled fin units in which the walls are substantially parallel and material is provided between the walls at their connected edges to anchor the walls in the grooves when pressure normal to the axis of the element on which the fins are mounted is exerted in the manner hereinafter described. The fin sections are pre-beat longitudinally to conform to the arc of the groove in which they are to be mounted and each section is preferably so dimensioned longitudinally as to occupy one half of the circumference of the groove.

The fin sections are initially placed in the grooves and successive sections are preferably staggered so that the ends thereof will not be disposed in alignment with the other sections. If desired, the sections in alternate grooves may be displaced around the circumference to the desired extent so that, as above stated, the division lines between the sections will not be disposed in alignment.

The fin sections may be temporarily secured by manually forcing the portions of the side walls into gripping engagement with the walls of the groove and after the fin sections have been mounted in the manner described, suitable means is actuated to insure the proper parallel relation of the fin walls and the proper alignment of the walls with presser bars which are thereafter manually moved between the walls of the fin sections under resilient pressure of a presser roll disposed therebeneath. These presser bars, which are preferably operated one at a time, exert pressure on the material disposed between the fin walls and expand the inner edges of these walls which are disposed in the groove into firm gripping engagement with the groove walls.

Further details of the invention will appear from the following description.

In the particular embodiment of the invention illustrated and in the particular machine or apparatus shown for carrying out the method, there is shown a machine supported on a base 29 having suitable legs 21, the base having secured thereto a pair of brackets, each having a base portion 22 secured to the base 29, an upright portion 23 and an upper laterally extending elongated portion 24.

The mandrel 25 is rotatably mounted in a bearing 26 carried by a bracket 27 mounted on the base 20. The rear end of the mandrel 25 is mounted in the bearing in a bracket 30 and has secured thereto a worm wheel 31 which meshes with a worm 32 carried by a shaft 33 on which is mounted a pulley 34. The pulley 34 is driven from any suitable source of power.

In the particular form of the invention shown, a cylinder 35 is mounted on the mandrel 25. The cylinder 35 has a flange 36 and the mandrel has secured thereto an arcuate block 37 which is undercut at 38 to receive the inner end of the cylinder and form an abutment therefor. The block 37 has a longitudinal opening 39 which receives a pin 40 which also extends through a bolt hole or opening 41 in the flange 36. The collar 37 is secured to the mandrel in any suitable manner, as by bolts 42.

In the form of the invention shown, the cylinder 35 is provided with a plurality of parallel circumferential grooves 43 which are adapted to receive the cooling fin sections.

The cooling fin sections, as shown in Fig. 3, are preferably semi-circumferential in length, or, in other words, each section is pre-curved or bent to conform to the curvature of the groove and is of sufficient length to occupy one half of the circumference of the groove.

The fin sections 50 are preferably formed with two walls 51 and 53 which, as shown in Fig. 14, are disposed substantially parallel and are spaced apart at their connected edges by an inwardly bent U-shaped loop 54 integral with the walls of the fin. The fin sections are anchored by forcing inwardly on the portion 54 between the fin walls, thus forcing the inner edges of the fin walls 51 and 53 laterally into firm gripping engagement with the walls 55 and 56 of the groove. The fin shown at the left in Fig. 14 is illustrated in anchored position in the groove.

The fin sections are initially placed in the grooves and temporarily anchored therein by manually forcing the material 54 between the fin walls inwardly by a tamping tool which is inserted between the walls 51 and 53. The material 54 may be forced inwardly, if desired, at the ends of the fin sections.

In order to prevent the cylinder wall from being forced out of alinement by pressure against the wall by the calking bars, the fin sections are staggered around the circumference of the cylinder so that the lines of separation between the sections will not be disposed in alinement. If desired, alternate fin sections may be offset circumferentially. For instance, one section may be advanced 90° from the preceding section or any desired arrangement can be used.

The elongated bracket portions 24 support trays 60 constructed as shown particularly in Figs. 6 and 7. Each tray has a base 61, side walls 62 and 63, a back wall 64 and at the opposite end thereof a plurality of equally spaced upwardly extending spacing plates 65 formed on or carried by a bar 74 which forms the front end of the base of the tray. The outer ends of these plates are pref-

erably tapered, as shown at 66, for a reason hereinafter explained. The plates 65 are spaced apart to receive therebetween presser bars 67 shown particularly in Figs. 8 and 9. These bars are flat and may, if desired, be provided with openings 69 to receive a suitable tool for moving the bars longitudinally. As shown in Fig. 1, one of the trays 60 is filled with spacing bars and the other tray is empty.

10 The trays are properly positioned on the bracket portions 24 by means of upwardly extending lugs 70 and 71 which are disposed at the ends of the bracket portion 24 and engage the side walls 62 and 63 of the trays. The inner portion of each bracket portion 24 is recessed, as shown at 73, to receive the cross bar 74 disposed on the bottom of the tray which further positions the tray on the bracket.

15 In order to insure the parallel relation of the fin walls 51 and 53 so that the calking bars or presser bars 67 will enter between the walls of the fin, suitable means is provided, as shown particularly in Figs. 3 and 15. This means consists of a shaft 75 which is rotatably mounted and has secured thereto a handle 76. The shaft 75 is mounted in brackets 77 carried by base portions 22 and extends through alined openings formed in the upper ends of a plurality of plates 78 which are mounted on rods 79 and 80 and are maintained in spaced relation by washers 81. The plates 78 are tapered, as shown at 81 in Fig. 11, to form flared openings therebetween at the right hand ends thereof, viewing Fig. 3. These openings between the plates are disposed in alinement with the openings between the plate 65 of the tray 60 and are adapted to receive and guide the calk bars 67 as these bars move forwardly between the walls 51 and 53 of the fin sections.

20 The shaft 75 has projecting laterally therefrom a spline bar 82 which extends through slots 83 formed in arcuate plates 84 mounted on the shaft 75 and tapered as shown in Fig. 13. The slots are larger in dimension than the spline bar 82 and thus permit a lost motion movement of the plates on the shaft relative to the spline bar 82.

25 In the position of plates 84 shown in Fig. 15, if the plates are properly alined with the opening between the walls 51 and 53 of the fin sections, they will drop into this opening, as shown at 85 in Fig. 15. However, if one of the walls is bent out of position, the plate 84 may strike against the outer edge of the wall, as shown at 86 in Fig. 15. This wall is then bent to permit the entry of the plate. After all of the plates 84 have dropped into the position shown at 85 in dotted lines, the handle 76 is rotated in an anti-clockwise direction, viewing Fig. 3, thus causing the spline bar 82 to move the plates to the position shown in Fig. 3, in which position they are disposed between the walls 51 and 53 of the fin sections.

30 When the fin walls have been properly alined, as above described, the calking bars 67 are moved one at a time longitudinally between the plates 78 and into the space between the walls 51 and 53.

35 In order to give the desired upward pressure to the calking bars so that material between the walls 54 will be forced inwardly to expand the walls laterally into anchored position, a presser roll 90 is mounted beneath the path of movement of the bars, this roll having a plurality of circumferential grooves 91 so spaced as to receive the bars 67, the distance between the grooves being

determined by the spacing of the fin sections on the cylinder wall.

The presser roll 90 has a cylindrical opening 92 which receives a shaft 93, the axis of the shaft being shown at 94. The shaft 93 has reduced end portions 95 mounted in ball bearings 96 and the outer ends of the shaft are further reduced as shown at 97, these outer ends being mounted in ball bearings 98. The outer ends 97 of the shaft are formed on an axis 99 which is eccentric to the axis 94 of the portion 92 of the shaft on which the roll 90 is mounted. A pair of arms 100 are secured to the reduced portions 95 of the shaft 93. The outer end of each arm 100 has pivoted thereon at 101, a vertically extending stud or bolt having a shank 102 which extends downwardly through an opening in the base 20. A spring 104 surrounds each of the shanks 102 and abuts against a shoulder 105 and at its opposite end against the upper surface of the base 20. Nuts 106 threaded on the lower end of the stem 102 limit the upward movement of the arm 100. The spring 104 tends to force the arm 100 in a clockwise direction about the axis 94. This tends to rotate the shaft 92 which, being eccentric to the ends 97 of the shaft, tends to elevate the roller 90 or to force it upwardly. This upward spring pressure is communicated to the calking bar and exerts a resilient upward pressure against the bar, thus forcing the bar with the desired pressure into the space between the fin walls 51 and 53 and forcing the material 54 between the fin walls inwardly to anchor the walls firmly in the groove.

Each calking bar 67 is initially moved by hand into operative position and as it moves between the portions 54 of the fin sections mounted on the cylinder carried by the rotating mandrel 25 and the presser roll 90 the calking bar will move longitudinally and during this movement exerts its calking action, thereby anchoring the fin section. The calking bar then moves between the plates 65 in the opposite tray 60. After all of the bars have performed their function the trays are then reversed, the full tray being placed in position to supply calking bars for the next calking operation.

From the foregoing specification it will be clear that a simple and practical method and apparatus have been provided for effectively and expeditiously calking fin sections and that the method described will effectively secure the fin sections around the cylinder wall or to the wall of the element to be cooled without distorting the wall or throwing it out of alignment.

Although one specific embodiment of the in-

vention has been particularly shown and described, it will be understood that the method and apparatus are not limited to the particular details set forth and illustrated but that changes in the method and in the apparatus may be made without departing from the spirit or scope of the invention, as expressed in the following claims.

What I claim is:

- 10 1. A machine for anchoring fin units having substantially parallel walls and compressible material between the walls in substantially parallel grooves of cylinders, comprising a rotatable support for the cylinder, means for supporting a plurality of individually movable presser bars in spaced relation and in alinement with the spaces between the fin walls of each fin unit, means for guiding said bars into said spaces to engage and compress or calk the material between said walls,
- 15 20 25
- means for receiving said bars after they have performed their calking operation and for maintaining the bars in their proper spaced relation, and a resiliently actuated grooved roller having a groove for each bar for guiding and forcing said bars against said compressible material to compress said material and force the portions of the fin walls in the grooves laterally into tight engagement with the groove walls.

2. A machine for anchoring fin units having substantially parallel walls and compressible material between the walls in substantially parallel grooves of cylinders, comprising a rotatable support for the cylinder, a presser bar disposed in alinement with the space between the walls of each groove and each unit disposed therein and movable thereto, and a resiliently actuated, grooved roller having a groove for each bar disposed adjacent the path of movement of each bar for pressing said bar into its space and against said compressible material as each bar is moved into operable position.
